UNITED STATES PATENT OFFICE.

KURT L. E. MUELLER, OF DETROIT, MICHIGAN, ASSIGNOR TO FREDERICK A. ROESE, OF MOUNT CLEMENS, MICHIGAN.

ROTARY OSCILLATORY ENGINE.

1,130,188.

Specification of Letters Patent.

Patented Mar. 2, 1915.

Application filed May 23, 1908. Serial No. 434,600.

To all whom it may concern:

Be it known that I, KURT L. E. MUELLER, a citizen of the United States of America, residing at Detroit, in the county of Wayne 5 and State of Michigan, have invented certain new and useful Improvements in Rotary Oscillatory Engines, of which the following is a specification, reference being had therein to the accompanying drawings.

10 The invention relates to explosion engines, and consists in the novel construction of a rotary oscillatory engine, as more fully hereinafter set forth.

In the drawings—Figure 1 is a vertical 15 longitudinal section through the engine; Fig. 2 is a cross section thereof; and Fig. 3 is a sectional view of the piston members detached. Fig. 4 is a diagrammatic illustration of the piston rod connections.

20 Generally described, my improved engine comprises a cylinder containing a rotary piston mounted upon a rockable shaft, the latter being so connected to a crank shaft as to effect an oscillatory movement of the 25 piston within the cylinder. As preferably constructed, two pistons are arranged within the cylinder, and are adapted to be oscillated in opposite directions thereby avoiding the necessity of any stationary abutments. The pistons separate the space within the cylinder into two compartments, one of which constitutes an explosion chamber and compression chamber, and the other a suction and compression chamber. Thus 30 the explosive mixture is first drawn into the cylinder in the chamber on one side of the pistons and is compressed therein, while at the proper time ports are opened through which the compressed discharge is passed 40 into the explosive chamber expelling the burned gases from a previous explosion.

In detail, A is a suitable base or bed upon which are mounted the cylinders B and B' arranged adjacent to each other, and within 45 each of which are two pistons C and C' adapted to oscillate. One of these pistons is mounted upon a central rock shaft D, while the other is secured to a concentric tubular rock shaft E, both of said shafts 50 passing out through the cylinder head, and being provided respectively with the rockable crank arms F and G. These crank arms are connected by rods H to a common crank I, the arrangement being such that

the rotation of said crank will produce an 55 opposite movement of the pistons C C' in each cylinder, but a simultaneous corresponding movement of said pistons in both cylinders.

One of the pistons C is provided at opposite ends with cheek plates J J' which fit against the heads K K' of the cylinder, while the co-operating piston C' is adapted to fit between these cheek plates. This co-operating piston is preferably mounted 65 upon the central shaft D and the tubular shaft E for the other piston is cut away between the cheek plates J J', leaving only a segment which bears against the shaft D. Suitable packing strips L are preferably 70 arranged to form a gas tight joint between this segment and the shaft D. Packing strips M are also provided for the pistons to form a gas tight joint with the cylinder.

The cheek plates J J' have formed there-in ports O, O' O', which in certain positions of the piston are brought into registration with ports P, P' P' in the opposite heads of the cylinder. The ports O, when in registration with the ports P, constitute exhaust 80 passages through which the products of combustion are permitted to escape from the explosion chamber, while the ports O' O', when in registration with the ports P' P', permit the transfer of the gases from the 85 suction chamber to the explosion chamber. This is accomplished by means of a connecting passage Q formed in the cylinder head with which both of the ports O' communicate thereby permitting the gaseous charge 90 to pass from one chamber to the other.

In addition to the ports above named, each of the cylinders has opening thereinto the passage R, in which an automatic valve S is located, this passage constituting the induction port through which the explosive mixture is introduced into the cylinder.

T is an igniter one arranged in each of the explosion chambers and connected to a suitable sparkling apparatus, not shown.

With the construction as described, when the parts are in the position illustrated in Fig. 1, a compressed charge of explosive gas is confined within the chamber U in the cylinder B, while an uncompressed charge of gas 105 occupies the chamber U' on the opposite side of the pistons. At the same time the cylinder B' has its pistons in a corresponding position,

the chamber V being filled with the products of a previous explosion, and the chamber V' contains a compressed charge about to be transferred to the chamber V. The explosion of the compressed charge in the chamber U will cause the opposite movement of the pistons C C' and the simultaneous movement of the pistons in the other cylinder B'. This will cause the compression of the charge 5 of gas in the chamber U' of the cylinder B and simultaneously the compression of the charge which has been transferred from the chamber V' to the chamber V in the latter chamber. At the completion of the first 10 phase of the oscillatory movement of the pistons, the ports O and P in the cylinder B are first brought into registration, permitting the gaseous products of the explosion in the chamber U to be exhausted. Immediately following this, the ports O P' are registered, which permits the charge of gas in 15 the chamber U', which has been compressed, to pass through said ports and the passage Q, entering the chamber U and expelling the remaining products of combustion. At this 20 point, the charge in the chamber V of the cylinder B', which has been compressed, is ignited, and the impulse of the explosion is transmitted through the rods to the crank 25 to continue its rotation. Thus there is an impulse for each half revolution of the crank similar to the organization of an ordinary steam engine.

While I have described a construction employing two cylinders having their pistons connected to a common crank, it is obvious that a single cylinder will form an operative construction.

The cylinders B B' are preferably 30 cased within a water jacket W, and water is also preferably introduced into each of the pistons which are hollow. The water entering the piston C' passes through the shaft D, while the other piston C receives its water supply through ports X in the cheek plates J J'. These ports communicate with the recess X' in the heads of the cylinder, and the arrangement is such that a water circulation is passed through the piston 45 without interfering with the oscillation thereof.

What I claim as my invention is:

1. The combination with a cylinder, of a pair of oppositely moving oscillatory pistons therein dividing the cylinder into suction and explosion chambers, means for admitting the explosive charge into said suction chamber and retaining it for a preliminary compression, and means for transferring 55 said compressed charge to the explosion chamber and for displacing the products of a previous explosion thereby.
2. The combination with a cylinder, of a pair of oppositely moving oscillatory pistons 60 therein dividing said cylinder into suc-

tion and explosion compartments alternately expanded and contracted, means for admitting an explosive charge into said suction chamber during the expansion thereof and for retaining it therein for a preliminary compression during the opposite movement of the pistons, and means operating upon the completion of said preliminary compression for transferring the compressed charge to the explosion chamber and displacing thereby the products of a previous explosion.

3. The combination with a cylinder, of a pair of oppositely moving rotary oscillatory pistons dividing said cylinder into alternately contracted and expanded explosion and suction chambers, valves operated by the movement of said pistons controlling the exhaust from said explosion chamber, and a passage between said suction and explosion chambers and an induction valve for admitting the explosive mixture into said suction chamber during the expansion thereof and for retaining it therein for a preliminary compression, said piston controlled valve operating upon the completion of said preliminary compression and transferring the compressed charge to said explosion chamber and displacing thereby the products of a previous explosion.

4. The combination of a pair of cylinders, a pair of oppositely moving rotary oscillatory pistons in each of said cylinders dividing the same into suction and explosion compartments, a common crank to which said pistons are connected, means for admitting an explosive mixture to the suction compartment during the expansion thereof and for retaining it therein for a preliminary compression, means for transferring the compressed charge to the explosion chamber of the same cylinder and for displacing thereby the products of a previous explosion, the operations in the two cylinders being alternate, and means for alternately exploding the compressed charges in the explosion chambers of the cylinders, whereby an explosion is given for each half revolution.

5. The combination with a cylinder, of a pair of rotary oscillatory pistons therein, a cheek plate attached to one of said pistons movable therewith in contact with the one head of the cylinder, said cheek plate and cylinder head being provided with co-operating ports which are thrown into registration at predetermined points in the movement of said pistons.

6. The combination with a cylinder, of a pair of oppositely moving oscillatory pistons therein dividing the cylinder into suction and explosion chambers, means for admitting an explosive charge into the suction chamber and for transferring the charge to the explosion chamber.

7. The combination with a cylinder, of a pair of oppositely moving rotary oscillatory pistons therein, means for admitting and compressing an explosive charge on one side 5 of said piston, means for transferring and exploding the explosive charge on the opposite sides of said pistons, and means for circulating a cooling fluid through each of

said pistons permitting of an oscillatory movement thereof. 10

In testimony whereof I affix my signature in presence of two witnesses:

KURT L. E. MUELLER.
